UNITED STATES PATENT OFFICE.

MEYER J. GOLDBERG, OF OIL CITY, PENNSYLVANIA.

DOUBLE-ACTING TWO-CYCLE ENGINE.

1,252,217.

Specification of Letters Patent. Patented Oct. 22, 1918.

Application filed September 11, 1916. Serial No. 119,492.

To all whom it may concern:

Be it known that I, MEYER J. GOLDBERG, formerly a subject of the Russian Empire, having received first naturalization papers for citizenship in the United States, and now residing at Oil City, in the county of Venango and State of Pennsylvania, have invented certain new and useful Improvements in Double-Acting Two-Cycle Engines, 10 of which the following is a specification.

The present invention relates to an engine which is rendered double-acting by providing two cylinders arranged in tandem with opposed open ends and pistons for the respective cylinders connected together, so that they act reciprocally; means being provided for supplying and exhausting a pressure medium, preferably a fuel exploded or burned within the cylinders; and particularly to that type of such engines in which pumping means are associated with pistons in order to develop a two-cycle operation.

A primary object of the invention is to develop an engine of this kind, especially adapted for large units, for instance 500 H. P., which will be of extreme simplicity in construction, of minimum dimensions over all, and of high relative efficiency, to which ends, the pistons are directly united by a yoke occupying the space surrounding the meeting ends of the pistons, and between the opposed ends of the cylinders, which yoke is developed as a pumping piston, as well as a coupling means for the working pistons and is surrounded by a cylinder in which it works, and which constitutes the spacing member for the working cylinders; the power-transmitting connection, in the form of a plurality of tie rods symmetrically spaced around the yoke (preferably two, located at opposite ends of a diameter), being extended longitudinally from the pumping piston, to a cross-head from which power may be transmitted in any suitable way, as for instance, through a pitman to a crank shaft.

Further objects relate to the development of certain auxiliary mechanisms which make for simplicity in construction and increased

efficiency, such for instance as the arrangement of ports controlled by the working pistons for the intake and discharge of pressure medium, and so relating these ports that the exhaust port and intake port are successively opened at the end of the working stroke, in the order named, with sufficient interval to dissipate the working pressure through the exhaust before opening the intake for fuel, and with sufficient lap to continue the exhaust opening during intake of fuel to insure scavenging, and at the same time utilizing the air pump to close the air passage and maintain sufficient pressure therein to resist back flow of air at the commencement of the compression stroke; also utilizing the yoke as a pumping connection for cooling water, as by providing it with telescoping tubes, acting upon the plunger pump principle in water chambers of the engine casing; also utilizing the connecting yoke and fuel-pumping piston with its cylinder as a dash pot or cushion to absorb the energy at the end of each stroke and assist in reversing the reciprocating movement of the engine; also providing certain other features of construction and operation, all of which will be hereinafter fully described and particularly pointed out in the claims; reference being made to the accompanying drawings, in which:

Figure 1 is a vertical axial section of an internal combustion engine embodying the several features constructed in accordance with the present invention;

Fig. 2 is an axial section of half of the cylinder structure remote from the power-transmitting connections, with the piston structure in full compression or ignition position therein; the section being on the same plane as that of Fig. 1 and upon an enlarged scale;

Fig. 3 is a transverse section through one of the cylinders in the plane of its exhaust, namely on the line 3^x—3^x of Figs. 1 and 2;

Fig. 4 is a section on the line 4^x—4^x of Fig. 1, showing the details of the cross-head, pitman connection and the cooling water exhaust;

Fig. 5 is a detail fragmentary view of the inner periphery of the cylinder showing the position of the exhaust ports;

Fig. 6 is a vertical transverse section illustrating the manner of "surcharging the cylinders"; and

Fig. 7 is a view similar to Fig. 6, but taken in quadrature thereto.

According to the preferred embodiment 10 of the invention here presented by way of illustration, a pair of cylinders 1, 1, arranged in tandem with closed outer ends and their opposed inner ends open, are fitted with pistons 2 united to form a unitary 15 reciprocally acting structure, the space 3 between the opposed ends of the cylinders being inclosed by a cylindrical wall 4, which reduces said space to an air-pumping chamber, and the connection between the pistons 20 being in the nature of a yoke 5 produced preferably by abutting flanges on the ends of the piston members, which yoke carries air piston members 5^a, which, fitting the inner wall of the cylinder 4, develop an efficient air pump in addition to guiding the yoke through which to transmit power from 25 the working pistons 2. The power-transmitting connections comprise a plurality of connecting rods 6, symmetrically spaced 30 around the circumference of the yoke piston (preferably two in number located at opposite ends of the diameter of the working pistons), and these connecting rods extend longitudinally from the piston yoke parallel 35 to the axis of the working pistons, through elongated bearings 7 in the engine casing, which makes the air-pumping chamber 3 sufficiently tight without stuffing box fittings, and to the cross-head 8 beyond the 40 end of the engine from which power may be taken off through any suitable connection, as for instance, the pitman 9 which in practice would preferably lead to a usual crank shaft. Each working cylinder 1 communicates with an exhaust pipe 10 through 45 means of a port 11 that is uncovered as the appropriate piston reaches the ends of its working stroke; also an air intake port 12 that communicates through an independent 50 air passage 13 with a port 14, opening into the air-pumping chamber 3 on the side of the piston yoke opposite from the particular port 12. The ports 14 are located in advance of the end of the air-pumping 55 stroke, so that while receiving a sufficient supply of air for a charge at each stroke of the engine, and compressing it in the passage 13 under sufficient pressure to promptly enter the working cylinder 1 as 60 soon as the port 12 is uncovered, said port 11 is cut off by the latter part of the stroke of the yoke piston to confine the stored charge in the passage 13 and prevent any back flow through the port 12 at the com-

mencement of the compression stroke of the 65 piston 2. This cutting off of the port 14 serves the further important purpose of developing a dash pot or fluid cushion at the end of each working stroke, which greatly assists the engine in changing the direction of its piston, and correspondingly relieves the train of connections from the fly wheel, besides contributing generally to the smoothness of running. An early cut-off 75 of port 14 has the further important advantage of providing a second stage for compression in the pumping cylinder. Reference should now be had to Fig. 7 where it will be seen that after port 14 has been cut-off a volume of air will be compressed 80 and forced past the check valve 35 into the storage compartment 36. After the piston 2 has passed by and cut off the port 11, the mechanically operated valve 38 is opened and the air confined within the compartment 85 36 rushes into the cylinder. This "surcharging" of the power cylinder is the means of increasing the power capacity of the machine without increase of the engine size. The delivery of air to the pumping 90 chamber 3 is through the port 15 which communicates through the annular space 16, with air supply pipe 17 leading from any suitable source.

Fuel injection will be upon any approved 95 system applied through the medium of the axial closures 18 of the cylinders 1.

From the foregoing description, it will be seen that the power-transmitting connections leading from the medial plane of the 100 piston structure are not in the form of a cross-head extending beyond the lateral lines of the cylinder structure as commonly practiced heretofore, but extending within the lateral confines of the cylinder structure, 105 and thus doing away with the considerable open space heretofore employed for a cross head or for laterally extending connections and correspondingly shortening the axial dimension of the whole engine structure. 110 It will also be seen that when this arrangement of transmitting connections has combined with it the air-pumping yoke, two 115 ends of the air-pumping chamber are united in a way that any leakage past the fuel pistons does not involve waste, since the escape is into the adjoining air space. It will further be seen that the parts are better balanced and alined, and withal the structure is greatly simplified.

A forced cooling circulation may be developed with peculiar advantage from the general plan of construction thus far described by utilizing the power-transmitting yoke 5 to operate telescoping circulating 125 connections. To this end, plunger pipes 19 project in the axial direction from the yokes 5, through stuffing boxes 20 into water

chambers 21, which are symmetrically spaced around the cylinder walls, being preferably two in number located at opposite ends of a diameter and they may be either in axial alinement with the connecting rod 6, or at right angles to or out of coincidence with the diametric positions of the connecting rods 6; chambers 21 being connected through pipes 22 with a water well 23 or other source of water supply. Thus, water in the chambers 21 can flow through the pipes 19 into the yoke 5 and thence through the circulating passages of the pistons 2, and thereby effectively cool the pistons. It can also flow through the water passages of the jacketed cylinders and effect the cooling of the latter in the usual way. To further induce the flow of water, the cross head 8 may be equipped with a similar telescoping plunger pipe 24 which enters a water chamber 25 in the cylinder and connecting at its cross-head end with a passage 26 which communicates with the bore 27 in one of the connecting rods 6. The bore 28 in the other connecting rod 6 communicates through passage 29 with the discharge pipe 30 which delivers into any suitable drainage passage 31.

In order to induce a prompt and complete evacuation of the working cylinder at the end of a working stroke, each exhaust port 11 is preferably sub-divided, as shown in Fig. 5, into primary discharge ports 11^a and secondary discharge ports 11^b. The primary ports 11^a communicate with a discharge nozzle 32 which is in ejector relation to the passage 33 which communicates with the ports 11^b, and since ports 11^a are longer than the ports 11^b and are uncovered first, a vigorous discharge takes place through the nozzle 32 and creates a partial vacuum in the passage 33. As soon as the ports 11^b are opened, the main body of the gases responds to this vacuum, with the result that considerable inertia is developed in the exhaust, and it is rendered much more complete and prompt than if the inertia of the air or spent gases in the discharge passage had to be overcome suddenly at the very end of the stroke. The loss of power due to exhaust through the advance ends of ports 11^a is comparatively slight. By the described arrangement, the main exhaust ports can be located quite near the end of the stroke, less gases will remain to contaminate the new charge, and the efficiency of the engine will be proportionately raised.

I claim:—

1. In a double-acting engine, a pair of opposed cylinders, a piston-structure reciprocating in said cylinders, and power transmitting connections extending from the piston-structure parallel to the axis of the cylinders, through the cylinder walls, but out-

side the working spaces of the cylinders; 65 said pistons being provided with a yoke extending radially beyond the piston-structure and receiving the transmitting connections; the opposed ends of said cylinders being spaced apart to receive said yoke; the space 70 between said cylinders being filled by a cylindrical wall providing an air-pumping chamber, and said yoke carrying a piston coacting with said wall; said air-pumping chamber having ports in communication with 75 the respective working cylinders and with a suitable air supply port common to each end of said air-pumping chamber.

2. In a double-acting engine, a pair of opposed cylinders, a piston-structure reciprocating in said cylinders, and power transmitting connections extending from the piston-structure parallel to the axis of the cylinders, through the cylinder walls, but outside the working spaces of the cylinders; said pistons 80 being provided with a yoke extending radially beyond the piston-structure and receiving the transmitting connections; the opposed ends of said cylinders being spaced apart to receive said yoke; the space between 85 said cylinders being filled by a cylindrical wall providing an air-pumping chamber, and said yoke carrying a piston coacting with said wall; said air-pumping chamber having ports in communication with the respective working cylinders and with a suitable air supply; said ports being controlled by the yoke piston. 90

3. In a double-acting engine, a pair of opposed cylinders, a piston-structure reciprocating in said cylinders, and power transmitting connections extending from the piston-structure parallel to the axis of the cylinders, through the cylinder walls, but outside the working spaces of the cylinders; said pistons 100 being provided with a yoke extending radially beyond the piston-structure and receiving the transmitting connections; the opposed ends of said cylinders being spaced apart to receive said yoke; the space between 105 said cylinders being filled by a cylindrical wall providing an air-pumping chamber, and said yoke carrying a piston coacting with said wall; said air-pumping chamber having ports in communication with the respective 110 working cylinders and with a suitable air supply; said ports being controlled by the yoke piston; the air outlet ports being closed by the yoke piston in advance of the end of its stroke. 115

4. In a double-acting engine, a pair of opposed cylinders, a piston-structure reciprocating in said cylinders, and power transmitting connections extending from the piston-structure parallel to the working spaces of 125 the cylinders; said pistons being provided with a yoke extending radially beyond the piston-structure and receiving the transmit-

ting connections; the opposed ends of said cylinders being spaced apart to receive said yoke; the space between said cylinders being filled by a cylindrical wall providing an air-pumping chamber, and said yoke carrying a piston coacting with said wall; said air-pumping chamber having ports in communication with the respective working cylinders and with a suitable air supply; said ports being controlled by the yoke piston, said air

supply being placed medially of said ports communicating with the working cylinders, whereby the said air supply is maintained closed by the said piston carried by the yoke, except at the ends of its stroke.

15

The foregoing specification signed at Oil City, Pennsylvania, this 21st day of August, 1916.

MEYER J. GOLDBERG.
